EDWARD J. KEARNEY, OF WAUWATOSA, AND JOSEPH B. ARMITAGE, OF MILWAUKEE, WISCONSIN, ASSIGNORS TO KEARNEY & TRECKER CORPORATION, OF WEST ALLIS, WISCONSIN

MILLING MACHINE

Application filed November 21, 1924. Serial No. 751,221.

This invention relates to improvements in milling machines and, more particularly, to a milling machine construction in which the over arms are mechanically adjustable.

5 It is the primary object of this invention to provide a novel and simple mechanical means for the adjustment of over arms such as are used in machine tools, and particularly in milling machines of the knee and column 10 type.

More specifically stated, it is the object of this invention to provide a mechanical device for adjusting the over arms of machines employing a plurality of such over arms, and to 15 provide for this purpose a simple adjusting device susceptible of manipulation for selectively adjusting any of a plurality of over arms independently or for simultaneously adjusting a plurality of over arms.

20 In the drawings:

Figure 1 is a side elevation of the upper portion of a milling machine column equipped with a device embodying this invention.

25 Figure 2 is a detail view on an enlarged scale taken on the section indicated at 2—2 in Figure 1.

Figure 3 is a detail view on an enlarged scale showing the milling machine column 30 broken away to expose its interior construction on the section indicated at 3—3 in Figure 1.

Figure 4 is a detail section taken on a reduced scale on line 4—4 of Figure 3.

35 Figure 5 is a detail section taken on a reduced scale on line 5—5 of Figure 3.

Figure 6 is a detail view in axial section on an enlarged scale of one of the pinions utilized to adjust the over arms.

40 Like parts are identified by the same reference characters throughout the several views.

The milling machine column 10 may be generally of any standard construction, with 45 the exception that it is preferably so organized as to provide vertical slots 11 opening into the bearings 12 in which the over arms 15 and 16 are axially adjustable. The slots 11 are traversed by a bolt 17 upon which the 50 nuts 18 are threaded for operative engage-

ment with those portions of the structure of column 10 which lie exteriorly adjacent the over arms. Thus, when either of the nuts 18 are tightened the over arms will be simultaneously clamped against axial movement by the springing of the column structure. This arrangement is more particularly described in a companion application No. 751,220, filed November 21, 1924.

55 There is preferably one of the above described bearings and clamps at the front of the column and an additional bearing and clamp at the rear of the column. The above description will apply in general to both clamps.

60 The over arms 15 and 16 are used for the support of a tool carrying, spindle driven, arbor 20 by means of pendants, one of which is shown at 21. This arrangement is described in the patent to Kearney & Trecker, No. 1,053,296, of February 18, 1913. Such over arms have heretofore been adjusted manually, the provision of means for adjusting them mechanically involving certain difficulties incident to the necessity for adjusting 70 the over arms independently at some times and simultaneously at other times.

65 In providing a simple device for the mechanical operation of the over arms we have found it convenient to utilize a transverse shaft 25 having a squared end 26 to which a crank 26' may be fitted, and from which it may readily be detached when desired. It will be noted from Figure 3 that this transverse shaft 25 extends through the boss, or pair of bosses, 27, which provides the rear-most bearing for the over arms 15 and 16. The shaft is disposed immediately beneath the over arms 15 and 16. The shaft 25 may conveniently be mounted in removable bearing members 28 which are held in place by suitable cap screws, as indicated in Figure 3, and permit the ready assembly upon shaft 25 of the pinions and of the clutch element hereinafter to be described.

90 The pinions 30 are in the nature of sleeves which are free to rotate upon shaft 25 except when clutched thereto. One of the pinions 30 is illustrated in an enlarged section in Figure 6, and inasmuch as these pinions may 95 100

be identical in construction the description of one will convey a proper understanding of both. Each pinion 30 is provided centrally with a bore 31 of a suitable size to receive the shaft 25. Suitable teeth 32 are milled in the periphery of the pinion. In the cylindrical end portion 33 is formed a transverse slot 34 adapted to receive ordinary clutch teeth on the axially shiftable clutch member 35.

10 Clutch member 35 is splined by means of a key 36 to shaft 25 in the usual manner. It is shifted by means of a fork 37 carried by an axially adjustable rod 38 having a bearing in the wall of the column 10, and having an additional bearing in the ear 39 which depends from boss 27.

It will be noted that each of the bearing members 28 is provided with a radially enlarged head adapted to receive the securing cap screws. At one side of the column this head is bored radially to provide a recess in which a spring pressed ball 40 is radially adjustable in the immediate proximity of the rod 38. The rod at this point is provided with a series of three grooves 41, which grooves are adapted to receive ball 40 in each of three predetermined positions of the shifting rod 38. When the rod is adjusted the ball will yield until it drops into the next succeeding groove of the series in impositive engagement. The clutch member 35 is shifted by means of the ancillary rod 38 instead of by an axial adjustment of the shaft 25 in order to obviate the possibility of an accidental shifting movement of the clutch during the rotation of shaft 25, and in order further to make it possible to remove instantly the crank from the squared end 26 of shaft 25. A more complicated attachment for such crank would be necessary if the crank itself were employed as a part of the means for shifting the internal clutch.

The length of the clutch sleeve 35 and of the teeth with which it is provided is so determined with reference to the spacing between the pinions 30 that the clutch, in the central position in which it is shown in Figure 3, may have its teeth engaged simultaneously with the clutch teeth (slot 34) of both of the pinions 30 the above one-half the depth of full mesh with each. From this central position the clutch may be adjusted axially in either direction for full mesh engagement with either of pinions 30 to the exclusion of the other. Thus, either or both of the pinions may be actuated by the rotation of shaft 25.

Each of the over arms 15 and 16 is provided integrally with rack teeth 45. The extremities of such rack teeth form, as indicated in Figure 3, a part of the bearing surface of the over arm and slide upon the bearing provided at 12 in boss 27. The position of pinions 30 is such that they mesh with the rack teeth, as indicated clearly in Figure

5. As shown in Figure 3, the axial spacing of the pinions is maintained by a spacing sleeve 46 within the clutch member 35 and upon shaft 25. In effect, this sleeve constitutes an enlargement of the shaft, providing shoulders against which the pinions abut. The key 36 extends through the sleeve into splined engagement with the shaft proper.

It will be noted that the pinions 30 are relatively very small. The use, therefore, of a suitable crank 26 to operate shaft 25 will enable the operator to exert a very considerable mechanical advantage upon either or both of the over arms. Power is available, therefore, for the actuation simultaneously of over arms which are comparatively very heavy.

We claim:

1. In a device of the character described, the combination with a column and a pair of over arms journaled therein, of a pendant provided with bores adapted to receive said over arms and solely supported, and mechanical means adapted selectively for the actuation of either of said over arms.

2. In a device of the character described, the combination with a column and a pair of over arms adjustable therein, of motion transmitting connections fixed against translatable movement with reference to the column and selectively operable to adjust either of said over arms, and including means for exerting a mechanical advantage for such adjustment.

3. In a device of the character described, the combination with a machine tool column and a pair of over arms adjustable independently therein, of a hand operated device for the adjustment of said over arms, and motion transmitting connections including a clutch mounted upon said column and adapted selectively to connect said device operatively with either of said over arms for their individual adjustment.

4. In a device of the character described, the combination with a machine tool column, a pair of over arms adjustable independently therein, and a pendant supported solely by said over arms, of a hand operated device for the adjustment of said over arms, and motion transmitting connections including a clutch associated with said column adapted selectively to connect said device operatively with either of said over arms for their individual adjustment, said connections including a prime mover so connected to said over arms as to operate over materially greater distance than an over arm in the adjustment thereof, whereby the resistance of the over arms to movement may be overcome with relatively light power.

5. In a device of the character described, the combination with a machine tool column and a pair of over arms independently ad-

justable therein, of a manually operable part, and a set of clutch-controlled motion transmitting connections in said column adapted to engage said part operatively with either of said over arms selectively and with both of said over arms for the actuation thereof respectively independently and simultaneously.

6. In a device of the character described, the combination with a machine tool column and over arms adjustable therein, of a rotor operatively connected with each of said over arms for the longitudinal adjustment thereof, a manually operable shaft, and a clutch adapted selectively to engage said shaft with either of said rotors.

7. In a device of the character described, the combination with a machine tool column and over arms adjustable therein, of a rotor operatively connected with each of said over arms for the longitudinal adjustment thereof, a manually operable shaft, and a clutch adapted selectively to engage said shaft with either of said rotors and optionally with both of said rotors simultaneously.

8. In a device of the character described, the combination with a milling machine column and a pair of adjacent over arms axially adjustable therein, said over arms being provided with rack teeth, of a shaft extending transversely with respect to said over arms, individual pinions meshing with the teeth of said over arms, and means selectively connecting either of said pinions to said shaft to be operated therefrom.

9. In a device of the character described, the combination with a milling machine column and a pair of over arms independently adjustable axially therethrough, said over arms being formed to provide rack teeth, of pinions engaged with the teeth of each of said over arms, a shaft co-axial with each of said pinions, and a clutch element connected with said shaft and adjustable between said pinions, said pinions being formed to receive engagement therewith, whereby said over arms may be selectively actuated by said shaft.

10. In a device of the character described, the combination with a milling machine column having a number of longitudinal bores and a set of over arms independently adjustable in said bores, of a transverse shaft, pinions on said shaft with their teeth intersecting said bores, said over arms being provided with rack teeth meshing with said pinions and adapted to ride in said bores, a clutch splined to said shaft and adjustably adapted in engagement selectively with said pinion, and means for shifting said clutch sleeve.

11. In a device of the character described, the combination of a column, over arms adjustable in said column and provided with rack teeth, aligned pinions meshing with the teeth of said over arms and axially spaced

apart, a shaft co-axial with said pinions, and a clutch element connected with said shaft and engageable with both of said pinions, said clutch element being of sufficient length to engage both of said pinions simultaneously, said element being engageable with either of said pinions to such an extent as to clear the other, whereby said pinions may be selectively actuated and may optionally be actuated simultaneously.

12. The combination with a milling machine column of a plurality of over arms adjustably mounted in said column and provided with rack teeth, a corresponding number of pinions engaging the rack teeth of respective arms, and a driving clutch element adapted to engage either of said pinions selectively and both of said pinions simultaneously.

13. The combination with a milling machine column of a plurality of over arms provided with bearings in said column and having rack teeth adapted to ride upon said bearings, a shaft extending transversely with respect to one of said bearings, pinions upon said shaft adapted to mesh respectively with the rack teeth of a plurality of over arms, a clutch member connected with said shaft and adjustable with respect to two of said pinions into positions of non-mesh, half mesh, and full mesh, said clutch element being of such a length as to be in half mesh with each of two pinions simultaneously.

14. The combination with a milling machine column provided with spaced longitudinal bores and with a transverse bore intersecting said longitudinal bores, bearing members fitted to said transverse bore to carry a shaft extending therethrough, a shaft journaled in said members, means providing teeth projecting from said shaft into each of said longitudinal bores, and over arms provided with rack teeth and mounted in said longitudinal bores, said rack teeth meshing with the teeth of said means, whereby said over arms are simultaneously adjustable.

15. In a device of the character described, the combination with a milling machine column providing spaced longitudinal bores, of a transverse bore intersecting said longitudinal bores, centrally apertured bearing members fitted within the ends of the transverse bore, a shaft journaled in said bearing members, pinions mounted on said shaft and having teeth projecting therefrom into said longitudinal bores, over arms in said longitudinal bores provided with teeth meshing with those of said pinions, and a clutch element mounted on said shaft and adjustable thereon between said pinions and adapted selectively to control the interaction of said shaft with said pinions.

16. The combination with a milling machine column and over arms adjustable there-

in in parallelism, said over arms being provided with rack teeth, of a transverse bore in said column, a shaft extending therethrough and carrying pinion teeth meshing with the teeth of said over arms, bearing members supporting said shaft in said transverse bore, a clutch element splined to said shaft and adapted for engagement with either and both of said pinions, a clutch shifting rod provided with notches, and a spring-pressed catch adapted impositively to engage said notches to define a plurality of operative positions of said clutch.

17. The combination with a milling machine column and over arms adjustable therein in parallelism, said over arms being provided with rack teeth, of a transverse bore in said column, a shaft extending therethrough and carrying pinion teeth meshing with the teeth of said over arms, bearing members supporting said shaft in said transverse bore, a clutch element splined to said shaft and adapted for engagement with either and both of said pinions, a clutch shifting rod provided with notches, and a spring-pressed catch adapted impositively to engage said notches to define a plurality of operative positions of said clutch, said catch being mounted in one of said bearing members.

18. The combination with a machine tool column provided with clamp bearings, of a transverse shaft mounted in association with one of said bearings, over arms provided with rack teeth and adjustable through said bearings, pinions carried by said shaft and meshing with the rack teeth of said over arms, and a clutch adjustable to a plurality of positions on said shaft for non-mesh, half mesh, and full mesh with each of said pinions, whereby said shaft may be operated selectively to actuate either of said over arms independently and, optionally, both of said over arms simultaneously.

19. In a device of the character described, the combination with a machine tool column provided with bearings, of over arms axially adjustable in said bearings, gears provided with teeth meshing with individual over arms for the adjustment thereof, and a shaft engaged with both of said gears for the simultaneous adjustment of said over arms, one of said gears having clutch means disengageably connecting it with said shaft whereby one of said over arms is independently adjustable.

20. In a milling machine having a column and a plurality of parallel over arms independently adjustably supported therefrom, the combination of adjusting means for said over arms including a part shiftable to different positions for actuation of the different arms and to another position for actuation of both of said arms, and means for operating said part in the various positions thereof whereby to actuate the particular over

arm or over arms with which it is engaged at the time of operation.

21. In a milling machine having a column and a plurality of parallel over arms movably supported therefrom, the combination of transmission mechanism for simultaneously moving said over arms, including a part journaled in said column and having connections within said column with each of said arms, one of said connections including a clutch disengageable, whereby to permit independent adjustment of one of said arms.

22. In a milling machine having a column and a plurality of parallel over arms supported therefrom for independent movement, the combination of a plurality of means for connecting said over arms for simultaneous movement, one of said means including a member provided with clutch mechanism selectively engageable with each arm for movement therewith and the other means including an actuating member mounted upon said column and operatively connected to actuate said member.

23. In a device of the character described, the combination with a column and a pair of over arms each independently guided therefrom, of mechanical means for the selective independent movement of either of said over arms, said means being alternatively operable to move both said over arms simultaneously.
